UNITED STATES PATENT OFFICE.

LOUIS A. MILLER, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

HAND-LAMP SWITCH.

1,368,278.

Specification of Letters Patent. Patented Feb. 15, 1921.

Application filed November 15, 1919. Serial No. 338,202.

To all whom it may concern:

Be it known that I, LOUIS A. MILLER, a citizen of the United States, residing at New Haven, in the county of New Haven, State of Connecticut, have invented certain new and useful Improvements in Hand-Lamp Switches; and I do hereby declare the following to be a full, clear, and exact description of the invention, such as will enable others skilled in the art to which it appertains to make and use the same.

The present invention relates to portable electric lights of the type wherein batteries and a lamp are contained in a suitable case, with switch mechanism conveniently positioned on the case to permit control of the current from the battery through the lamp.

With hand lamps of this general character, the batteries have often been ruined by accidental closing of the switch or contact device when the lamp was carried in a tool kit, or in a trunk, or where pressure might be applied to the push button of the switch without the knowledge of the user.

It is an object of the present invention to provide a contact device having a flexible contact member with a push button by which the member may be manually actuated to flash the lamp, but with means movable over said push button to prevent accidental pressure thereon when lighting of the lamp is to be avoided. In the advantageous embodiment hereinafter described, the movable member which acts as a guard for the button can also be used for holding the button depressed when a continuous light is desired.

Other objects and advantages will be apparent from the following detailed description, which is to be taken in conjunction with the accompanying drawings, wherein—

Figure 1 is a longitudinal section of the hand lamp and its switch;

Fig. 2 is an enlarged plan of the switch mechanism;

Figs. 3 and 4 are longitudinal sections on the lines 3—3 and 4—4, respectively, of Fig. 2, and show the push button in its normal or open-circuit position;

Figs. 5 and 6 correspond with Figs. 3 and 4, excepting that the thumb-piece has been moved forward to override and permanently depress the push button;

Figs. 7 and 8 correspond with Figs. 3 and

4, excepting that the thumb-piece has been pushed still farther forward to release the push button, for which the thumb-piece then serves as a housing; and

Fig. 9 is a transverse section on the line 9—9 of Fig. 5.

In the embodiment illustrated, the hand lamp comprises a series of two or more dry cells 1 placed end to end with the naked bottom of the lowermost cell resting on a coiled spring 2 which is carried by a metal cap 3 threaded to a collar 4. This collar is in electrical connection with a conductor 5, the upper end of which is secured to the switch mechanism as by a rivet 6.

The tube 7, in which the batteries are housed, may be of fiber or like insulating material, and carries at its front end a threaded collar 8, a lens 9, a lens-holding ring 10, and a reflector 11. The incandescent lamp 12 has its inner terminal in electrical connection with the center or carbon electrode 13 of the topmost dry cell, and its outer or threaded terminal connected, as through reflector 11, with a conductor 14, leading to a rivet 15 or equivalent lug serviceable as one contact member of the switch mechanism. Preferably, the conductor 14 and the outer terminal of the lamp are insulated from rings 8 and 10 to prevent inadvertent lighting of the lamp when laid on a metal surface.

The contact mechanism illustrated more in detail in Figs. 2 to 9 comprises an escutcheon 16, carrying a housing 17, which may be integral therewith. Within this housing is a contact element in the form of a spring finger 18, secured at one end to the housing, as by means of a hollow rivet 19, and carrying at its other end a push button 20 by which the contact member may be manually operated to flash the lamp in usual manner. Housing 17 is provided with relatively long slots 21 and 22 to serve as guide-ways for the outwardly clenched tangs 23, 24 (Fig. 9) of a hollow thumb-actuated member 25. This member is shaped at its front end to form a pocket 26 so that when the member is pushed forward by thumb pressure, it will overrun button 20 and thereby depress the button and hold it in closed-circuit position. A shoulder 27 tends to limit forward movement of member 25. However, if lighting of the lamp is to be

avoided, as when the hand lamp is packed away in a tool kit, member 25 can be pushed farther forward until its shoulder 27 slips over button 20 to the position shown in Fig. 5. Push button 20, being thus released, swings out to open-circuit position and is housed within and guarded by the sliding member 25.

It is advantageous to form a projection 28 on the rear, flat part of the sliding member, for in the normal position shown in Fig. 3, this projection will be received in the opening of rivet 19 and will serve to prevent a too easy forward movement of the member. 10 And, similarly, in the position shown in Fig. 7, this projection may be received in a corresponding depression in the housing, and will serve to prevent a too easy backward movement of the sliding member. 15

20 To accentuate this locking effect in these two positions, I prefer that the sliding member 25 shall rest on runners having their front edges beveled or rounded off, as shown in Fig. 9. These runners, on reaching the 25 ends of their respective slots, ride up, and so tilt the sliding member from the position shown in Fig. 6 to the position shown in Fig. 4, or the opposite position shown in Fig. 8. This rocking movement has a tendency to flex the top face of housing 17 so that projection 28 enters the depressions on the forward and backward limits of its 30 sliding movement with rather more snap than would otherwise be the case.

35 I claim:—

1. A contact device for a battery hand lamp having a push button manually operable to flash the lamp, and a member for holding said push button in depressed position when desired, said member also being adapted to serve as a housing for said push button when lighting of the lamp is to be avoided. 40

2. A contact device for a battery hand lamp, having a push button manually operable to flash the lamp, and a member

adapted to slide forward and overrun the button when a continuous light is desired, and also adapted to serve as a housing for said push button when lighting of the lamp 50 is to be avoided.

3. A contact device for a battery hand lamp having a push button manually operable to flash the lamp, and a thumb-piece adapted to slide forward and depress said button when a continuous light is desired, 55 said thumb-piece being movable forward still farther until it releases the button; substantially as described.

4. A contact device for a battery hand lamp comprising a housing, a flexible contact member secured at one end to said housing and having at its other end a push button manually operable to flash the lamp, and a hollow thumb-piece adapted to slide along 60 said housing and overrun said button when a continuous light is desired, said thumb-piece being movable still farther to release the button and serve as a housing therefor when lighting of the lamp is to be avoided. 70

5. A contact device for a battery hand lamp comprising a housing, a spring finger therein having one end fastened to the housing and having at the other end a push button manually operable to flash the lamp, 75 and a hollow thumb-piece movable along guide-ways in said housing and adapted to overrun and depress said button when a continuous light is desired, and movable still farther to release the button and to serve as 80 a housing therefor when lighting of the lamp is to be avoided.

6. A contact device for a battery hand lamp comprising a housing, a spring member attached at one end to said housing and 85 carrying at its other end a push button manually operable to flash the lamp, and a thumb-actuated member slidably forward to serve as a housing for said push button when lighting of the lamp is to be avoided. 90

In testimony whereof I affix my signature.
LOUIS A. MILLER.
